2,442,540

ENGINE COOLING CYLINDER AND JACKET
CONSTRUCTION

James B. Fisher, Waukesha, Wis., assignor to
Waukesha Motor Company, Waukesha, Wis., a
corporation of Wisconsin

Application February 15, 1946, Serial No. 647,766

5 Claims. (Cl. 123—173)

1

This invention relates to internal combustion engines, and has to do with means for controlling admission and distribution of a coolant, usually water, to and in the cylinder block of the engine.

In operating internal combustion engines on kerosene and distillate excessive wear of certain of the cylinders, or cylinder barrels, occurs, which is objectionable for obvious reasons. The wear of the cylinder is caused by inadequate lubrication, due to dilution of the lubricating oil with unburned fuel. That is caused mainly by condensation of the fuel on the cylinder walls. I have found that the relatively cold water entering the cylinder block at the upper portion thereof, as is the usual practice, tends to chill the upper portions of the cylinders, in the area of the combustion space, with the result that the entering fuel condenses on the cylinder walls causing dilution of the lubricating oil. For example, in an engine in which the water pump is mounted on the front of the cylinder block, which is common practice, the water is discharged directly into the cylinder block and impinges on the walls of the front or number one cylinder. I have found that in such engines of four cylinders, there is a considerable difference in temperature between the cylinders, due to the effect of the entering cooling water referred to, so that the second cylinder runs somewhat warmer than the first cylinder, and the third and fourth cylinders run considerably warmer than the first cylinder. In such an engine considerable dilution of the lubricating oil by unburned fuel occurs, particularly in the first cylinder, with the result that excessive wear of that cylinder occurs and, to a slightly less extent, also of the second cylinder. What has been stated with respect to an engine operating on kerosene or distillate applies, in general, though to less extent, to engines operating on gasoline. Accordingly, it will be understood that though my invention is concerned particularly with engines operating on kerosene and on distillate it may be applied to advantage to engines operating on gasoline.

My invention is directed to avoiding the above noted objections with respect to cooling of the cylinders, in internal combustion engines of the type above referred to. To that end, I provide improved means, of simple and inexpensive construction, whereby the cooling water entering the cylinder block is so distributed as to avoid objectionable cooling of the cylinders, particularly at the upper portion thereof. Preferably, the cooling water distribution means of my in-

2

vention is of such character that the water intake therefor is disposed at one end of the cylinder block, so that the water pump may be mounted on the end of the cylinder block, if desired, as is frequently done. Further objects and advantages of my invention will appear from the detail description.

Figure 1 is a side view of an internal combustion engine embodying the cooling water distribution means of my invention, many of the accessories being omitted for clearness of illustration;

Figure 2 is a front end view of the engine of Figure 1;

Figure 3 is a plan view, partly broken away and on an enlarged scale, of the cylinder block of the engine of Figure 1, with the water pump shown fragmentarily and partly broken away and in section, and the adjacent portion of the cylinder block partly broken away and in section;

Figure 4 is a fragmentary end view of the cylinder block of Figure 3, on an enlarged scale, looking at the cooling water intake end thereof;

Figure 5 is a sectional view, on an enlarged scale, taken substantially on line 5—5 of Figure 3;

Figure 6 is a sectional view taken substantially on line 6—6 of Figure 3;

Figure 7 is a sectional view, on an enlarged scale, taken substantially on line 7—7 of Figure 3; and

Figure 8 is a sectional view, on an enlarged scale, taken substantially on line 8—8 of Figure 3.

I have shown the cooling water distribution means of my invention, by way of example, as applied to an internal combustion engine which is, in general, of known construction and operation. It comprises a cylinder head 10, a cylinder block 11, which may be cast as usual, crank case 12 and oil pan 13, all of which are bolted together in accordance with the usual practice. A water outlet fitting 14 is mounted on an outlet member 15 of cylinder head 10, in communication with the cooling water space thereof, and is connected by a suitable hose (not shown) to the inlet at the top of the radiator (not shown) positioned in front of engine E. The outlet, at the bottom of the radiator, is connected by a conduit 16 to the intake of a water pump 17. The pump 17 is included in a pump and fan unit assembly A of suitable construction and operation. A fan 18, with an associated pulley 19, is suitably secured on shaft 20, on which impeller 21 (Figure 3) of pump 17 is also secured. The inner or base end of pump housing 22 is closed by a base plate 23 suitably secured thereto, with an intervening

gasket *g*. Plate *d* is provided adjacent one side thereof with a discharge opening *18*. The pump is also provided with a by-pass intake connected by a by-pass conduit *c* to the fitting *14*, as is known. The base of the pump housing *h* is bolted to the front cylinder block *11*, at the top thereof, with discharge opening *18* overlying the water intake opening in the block, as will be explained more fully presently. A belt *b* passes about a V-pulley *a*, driven in a suitable manner by the engine, and thence over pulley *p*, belt *b* also passing over a V-pulley *e* of a generator *k* suitably mounted at one side of the cylinder block *11*. The pump *17* is thus driven in the operation of the engine, as is the fan *f* and the generator *k*. It will be understood that any suitable pump, driven in any suitable manner, may be used, the pump *17* and the drive therefor being shown by way of example only. As above noted, the engine *E* is illustrated rather diagrammatically, many of the appurtenances being omitted, for clearness of illustration.

It may be assumed that the engine *E* is a four cylinder engine, for purposes of description. The cylinder block *11* is substantially rectangular in plan, as usual, and is provided through its top wall *20* with suitably disposed rabbeted openings *21* in which seat the flanged upper ends of cylinder barrels *22* which define the cylinders of the engine. The barrels *22* pass downward through a lower wall *23* of cylinder block *11* with a sealing fit therethrough. The block *11* and the cylinder barrels *22* therein together define a cooling water space about the cylinders, as will be understood, and this space communicates, through suitable openings in top wall *20* of block *11* and in the lower wall of cylinder head *10*, with the water space of the latter. In the operation of pump *17*, relatively cold water is taken from the radiator at or adjacent the bottom thereof and is delivered to the cylinder block *11* through opening *18*, this water passing from the cylinder block into the cylinder head *10* and thence to the upper portion of the radiator, by way of member *15* and fitting *14*, as is known.

The cylinder block *11* is provided at the top of one corner thereof with a water intake passage *25* defined by an inner wall *26* and top and bottom walls *27* and *28*, respectively, shown more clearly in Figures 3 and 4, integrally connecting wall *26* to the adjacent side and end walls *29* and *30*, respectively, of block *11*. Passage *25* opens, at its outer end, through a bolting pad *31* formed on the end of cylinder block *11*, to which pad the pump *17* is bolted, with discharge opening *18* thereof in overlying relation to intake opening *32* at the outer end of passage *25*. The inner end portion of wall *26* extends in spaced parallel relation to side wall *20*, as in Figures 2 and 4. Cylinder block *11* further is preferably provided with transverse reenforcing web elements *33* extending from the side walls thereof between the cylinders.

Side wall *29* of block *11* is provided, at the upper portion of its inner face, with upper and lower ribs *34* and *35*, respectively, extending lengthwise thereof and spaced vertically a substantial distance apart. These ribs extend between and are formed integrally with the web elements *33*, and also extend from the front or first web element *33* to the top and bottom walls *27* and *28*, respectively, of the inner end portion of the intake passage *25*, constituting extensions of such top and bottom walls. Conveniently, the

inner faces of the ribs *34* and *35* are flush with the inner face of inner wall *26* of passage *25*.

A cover plate *36*, rectangular in shape and preferably formed of galvanized sheet steel, is secured to side wall *29* of cylinder block *11*, seating at its forward end portion on the inner end portion of wall *26* of passage *25* and, at its top and bottom portions on ribs *34* and *35*, the inner end of plate *36* being disposed closely adjacent the first web element *33* with but slight clearance, if required, to accommodate expansion thereof. In Figure 5, the clearance *38* between the inner end of plate *36* and the web element *33* has been exaggerated for clearness of illustration, as will be understood. Plate *36* is secured in position by means of headed screws *40* passing therethrough and threading into suitably bored and tapped bosses *41* formed integrally with side wall *29* of cylinder block *11*. The outer ends of the bores of bosses *41* are closed in any suitable manner, conveniently by headed screws *42* threaded therein, with copper washers *43* disposed between the heads of the respective screws and the outer face of wall *29*. A second plate *45*, similar to but somewhat longer than plate *36*, is secured to wall *29* between the first and second web elements *33*, seating at its upper and lower portions on the ribs *34* and *35*, as shown.

It will be seen that the plates *36* and *45* define, with the ribs *34* and *35* and the portion of wall *29* therebetween, a water inlet passage *47* freely opening at its outer end into the inner end of the water intake passage *25*. The first web element *33* is cored out, providing an opening *48* therethrough preferably of the same cross section as passage *47*, providing free communication between the portions of this passage corresponding to the plates *36* and *45*. The lower rib *35* has its inner end spaced from the second web element *33*, (Figure 6) providing therewith a downwardly directed discharge opening *49* from the water inlet passage *47* into the cooling water space within cylinder block *11*. Also, the second web element *33* is provided therethrough with a discharge opening *50* and, at the top thereof, a downwardly and inwardly inclined baffle *51*, which deflects the water discharged from passage *47* downwardly into the cooling water space of cylinder block *11*.

It will be seen that the cooling water entering through passage *25* flows through passage *47* to about the midlength of the cylinder block *11* and is there discharged downward into the cooling water space surrounding the cylinders, thereby guarding against chilling of the upper portions of the cylinders, particularly the first and second cylinders. In that manner I guard against condensation of fuel on the cylinder walls and resultant dilution of the lubricating oil with consequent objectionable wear of the cylinder barrels, above referred to. It will be noted that the use of the cooling water distribution means of my invention entails no substantial change in the cylinder block *11*, the ribs *34* and *35* and the space therebetween being formed by simple cores, as are the opening *48* in the first web element and the opening *50* in the second web element *33*, the lower rib *35* being formed of proper length to provide the opening *49*, in the casting operation. By using the plates *36* and *45* to provide the inner wall for the passage *47*, I avoid necessity of expensive coring operations and am enabled to form the inner wall of the passage *47* much thinner than would be possible if this passage were formed entirely as a casting constituting an integral part

of the cylinder block 11, which is conducive to simple and inexpensive construction. It will also be seen that by the cooling water distribution means of my invention the water pump may be mounted directly on the end of the cylinder block, without risk of objectionable chilling or cooling of the first and second cylinders, since the entering cooling water enters the water space within the cylinder block at a point remote from such cylinders, as above described.

I claim:

1. In an internal combustion engine, a cylinder block and cylinders therein together defining a cooling water space about said cylinders, vertically spaced lengthwise ribs at the inner face of the upper portion of said side wall, and closure plates secured to said wall seating on said ribs defining therewith and with the portion of said wall therebetween a water inlet passage, said passage communicating with a water intake opening at one end of said block and having a downwardly directed discharge opening into said space remote from said intake opening.

2. In an internal combustion engine, a cylinder block and cylinders therein together defining a cooling water space about said cylinders, reinforcing web elements extending from the side walls of said block transversely thereof between said cylinders, vertically spaced ribs at the inner face of a side wall of said block extending lengthwise thereof between certain of said web elements, and closure plates secured to said side wall extending between certain of said web elements and seating on said ribs defining therewith and with the portion of said wall therebetween a water inlet passage, said passage communicating with a water intake opening at one end of said block, the bottom one of said ribs having its inner end spaced from one of said web elements providing a downwardly directed discharge opening from said passage into said space and said one web element having therethrough a discharge opening from said passage into said space.

3. In an internal combustion engine, a cylinder block and cylinders therein together defining a cooling water space about said cylinders, said block having at one end thereof an intake passage defined in part by a side wall of said block provided at its outer end with an intake opening adapted for connection to the discharge of a cooling water pump, vertically spaced lengthwise ribs at the inner face of said side wall, and closure plates secured to said side wall seating on said ribs defining therewith and with the portion of said wall therebetween a water inlet passage opening at its outer end into the inner end of said intake passage, said inlet passage having a discharge opening into said space remote from its outer end.

4. In an internal combustion engine, a cylinder block and cylinders therein together defining a cooling water space about said cylinders, said block having at one end thereof an intake passage defined in part by a side wall of said block pro-

vided at its outer end with an intake opening adapted for connection to the discharge of a cooling water pump, the inner end portion of said passage being of substantially rectangular cross section, vertically spaced lengthwise ribs at the inner face of said side wall extending from the top and bottom walls of the inner end of said intake passage, and closure plates secured to said side wall seating on said ribs defining therewith and with the portion of said wall between said ribs a water inlet passage extending from the inner end of said intake passage and having a downwardly directed discharge opening from said inlet passage adjacent the inner end thereof into said space.

5. In an internal combustion engine, a cylinder block and cylinders therein together defining a cooling water space about said cylinders, said block having at one end thereof an intake passage defined in part by a side wall of said block provided at its outer end with an intake opening adapted for connection to the discharge of a cooling water pump, the inner end portion of said passage being of substantially rectangular cross section, reinforcing web elements extending from said wall of said block transversely thereof, vertically spaced lengthwise ribs at the inner face of said side wall extending from the top and bottom walls of the inner end of said intake passage to one of said web elements and between certain thereof, and closure plates secured to said side wall seating on said ribs defining therewith and with the portion of said wall therebetween a water inlet passage extending from the inner end of said intake passage, the web element between said plates having an opening therethrough constituting a portion of said inlet passage, the bottom one of said ribs having its inner end spaced from the innermost one of said web elements providing a downwardly directed discharge opening from said inlet passage into said space, the innermost one of said web elements having an opening therethrough from said inlet passage with a baffle disposed to deflect downwardly into said space water flowing through said last mentioned opening from said inlet passage.
